(57) **CLAIM**

The ornamental design for an induction cooktop, as shown and described.

DESCRIPTION

FIG. 1 is a front perspective view of an induction cooktop, showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is an enlarged view of the encircled 8 in FIG. 1

FIG. 9 is an enlarged view of the encircled 9 in FIG. 1;

FIG. 10 is an enlarged view of the encircled 10 in FIG. 6;

FIG. 11 is an enlarged view of the encircled 11 in FIG. 6;

FIG. 12 is an enlarged view of the encircled 12 in FIG. 6;

and,

FIG. 13 is an enlarged view of the encircled 13 in FIG. 6.

The even-dash broken lines illustrating portions of the induction cooktop form no part of the claimed design. The dot-dash broken lines encircling enlargement portions of the claimed design form no part of the claimed design.

1 Claim, 13 Drawing Sheets
